COIN-COUNTING MACHINE

Arnold R. Buchholz, Watertown, Wis., assignor to
Brandt Automatic Cashier Company, Water-
town, Wis., a corporation of Wisconsin

Application April 18, 1951, Serial No. 221,709

2 Claims. (Cl. 133—8)

1

The invention relates to coin counting machines for automatically counting either an unlimited or predetermined number of coins of different denominations.

More particularly, the invention relates to that type of coin counting machine in which the coins are fed into a hopper having a revolving plate for its bottom by which the coins are fed by centrifugal force toward the periphery of the hopper which has an opening at one side formed in part by an adjustable gate through which opening coins pass to a discharge passage along which the coins are fed by a feed wheel past a counter operating star wheel prior to their discharge from the machine. In the copending applications Serial No. 115,272, filed September 12, 1949, of Earl W. Quirk and Arnold R. Buchholz, and Serial No. 181,713, filed August 28, 1950, of Arnold R. Buchholz and William H. Sprenger, there is disclosed a machine of the general type above described in which a continuously rotatable feed wheel is tiltably mounted for movement to a coin feeding position and to an inoperative position, the tilting movement being controlled by one revolution actuating mechanism controlled by predetermined count mechanism, which mechanism is preferably of the type shown in U. S. Patent No. 2,378,828, dated June 19, 1945, to A. R. Buchholz et al. One of the objects of the present invention is to provide improvements in the aforementioned applications. One of these improvements is a new improved swinging mounting for the coin feed wheel by which the shaft for the wheel instead of being mounted to swing only on a medially disposed pivot connection between its mounting and the thickness gauge now swings directly about the outer end of said gauge, so that the pulley carried by the outer end of this shaft is only given a slight angular movement on the swinging of the wheel shaft to its operative and inoperative positions, so that there is less wear on the drive belt associated with this pulley, and so that at its front end its mounting forms a part of a pull down lever pivotally connected intermediate its end with the thickness gauge to provide an increased leverage effect on the bearing arm.

Another improvement is in the control by the predetermined count mechanism of the latch which holds the feed wheel in its coin feeding position. In the present application, the holding latch is connected to the predetermined count mechanism by a lever and link that is operated on by the star wheel driven shaft at the end of a predetermined count to exert a latch-releasing

2

pull on said link, whereas the above referred to applications used a pushing action. It has been found that the present construction of latch release mechanism hereinafter described requires less force to release the holding latch.

The invention further consists in the several features hereinafter described and more particularly defined by claims at the conclusion hereof.

In the drawings:

Fig. 1 is a plan view of a coin counting machine embodying the invention;

Fig. 2 is a side elevation view of the machine;

Fig. 3 is a horizontal sectional view of the machine looking into it from the underside taken generally along the line 3—3 of Fig. 2 and with the motor removed;

Fig. 4 is a front elevation view of the machine, parts being broken away and parts being shown in section showing the coin feeding wheel in feeding position;

Fig. 5 is a detailed elevation view of the feed wheel mounting, parts being broken away and parts being shown in section;

Fig. 6 is a detailed vertical sectional view taken on the line 6—6 of Fig. 4;

Fig. 7 is a detailed view of parts of the predetermined count mechanism.

Referring to the drawings, as in all machines of this general type, a counter 10 is provided which, as shown in Fig. 4, carries a bevel gear 11 meshing with a bevel gear 12 on an upright counter drive shaft 13 carrying a coin operated star wheel 14, the coins being fed past said wheel 14 by a feed wheel 15 as they are delivered to the wheel 14 through an adjustable opening at one side of a hopper 16 whose bottom 17 is a rotary plate carried by a vertically disposed shaft 18 suitably journaled in the top plate 19 and carrying a spiral gear 20 meshing with a spiral gear 21 on the main drive shaft 22. See Figs. 1, 3 and 4.

As in the Buchholz et al. patent, the adjustable gate 23, which determines the height of the side discharge opening from the hopper 16 to accommodate the thickness of the particular denomination of coin is vertically adjustable by the turning of a screw shaft carrying a handle 24. Also in accordance with known practice, a gauge plate G is slidably mounted relative to the star wheel 14 to adjust the width of the passage between the star wheel and plate for the diameter of the particular denomination of coins being counted and is locked in position by a hand clamp C.

Beyond the wheel 14, the discharge passage is formed by a chute 25 which discharges the

counted coins into a tube section 26 which has a coin reflector 27 projecting above the outlet of the chute 25. The tube section 26, as in the aforementioned applications, discharges into a tiltable discharge tube 28 which acts through a plunger therein shown to operate a rock shaft 29, pivoted at 30 and operatively engageable with a lever 31 pivotally connected at 103 to a count starting control member 98 hereinafter described, so that either tilting of the tube or a direct movement of the member 98 will start the count.

Referring to Fig. 2, an electric motor 32 has a pulley 33 mounted on its drive shaft and connected by a belt 34 with a pulley 35 on the main drive shaft 22.

Referring to Figs. 2 and 4 to 6, the feed wheel 15, which has a rubber coin contacting face 15a, is mounted on a shaft 36 carrying a pulley 37 connected by a belt 38 with a pulley 39 on the drive shaft 22. The shaft 36 is mounted in a rear bearing 40 and a front bearing 41. Unlike the aforementioned applications, as shown in Figs. 4 and 5, the rear bearing 40 is mounted in trunnions 42 which are carried by the arms of a bracket 43 fixed directly to the thickness gauge or gate 23. The front bearing 41, as shown in Fig. 6, is vertically adjustably mounted in a box 44 at the end of one arm of a tiltable lever support 45 which is mounted intermediate its ends to turn about a pivot shaft 46 anchored in the gauge or gate 23 and whose other longer arm at its outer end is connected with tilting means hereinafter described. By this arrangement while the feed wheel carrying end of the shaft is tilted up and down by means acting on one arm of the tiltable lever support 45 as hereinafter described, the rear bearing tilts about the relatively fixed pivot provided by the trunnions 42 which are close to the pulley 37 so that this pulley only swings through a small arc, and thus the life of the belt running over this pulley is conserved since there is less side wear on the belt when the shaft 36 is tipped up. In the tilting of the shaft 36 on the trunnions 42 by the swinging of the lever 45 this shaft is free to slide slightly in its front bearing 41 to compensate for the arcuate movement of the lever 45 and box 44 about the pivot 46. As in the aforementioned applications, the front bearing 41 is vertically slidably mounted in the box 44 formed as a part of the support 45 and has a threaded bore 47 engaged by a manually adjustable screw shaft 48 journalled in the top wall of the box, so that turning of the shaft will move the bearing 41 relative to said support so that the shaft 36 may be tipped slightly relative to the rear bearing 40 to compensate for wear of the face 15a. The shaft 48 is turned by a thumb wheel 49 of the locking type, that is, it is lengthwise movable on the shaft 48 and yieldingly urged toward the box 44 by a spring 50 so that its diametrically disposed projections 51 may engage in similarly disposed recesses 52 in the top of the box.

The support 45 may be moved to a feed wheel inoperative position by any suitable means which, as shown here, is the spring of a belt tensioner acting on the belt 38 and a spring 45a interposed between the box 44 and the plate 19. The tensioner (see Figs. 2 and 3) includes a pulley 53 engageable with the belt 38 and carried by an arm 54 mounted to swing on a fixed stud 55 and urged to a tensioned position by a spiral spring 56 which has the effect of pulling down on the pulley carrying end of the shaft 36 when permitted to do so and thus with the aid of the

spring 45a swing the feed wheel 15 to an inoperative position.

The support 45 is moved to feed wheel operative position by a one revolution operating means actuated by the drive shaft 22 and controlled by the predetermined count mechanism, and the preferred form of this mechanism is more particularly shown, described, and claimed in the copending application Serial No. 181,713, Fig. 4 of this case corresponding to Fig. 5 of that application and being considered sufficient for an understanding of the improvements hereinafter described relating to the means for holding the wheel shaft 36 and the wheel 15 in its coin feeding position and the release of said holding means at the end of a predetermined count. Referring to Figs. 3 and 4, the one revolution operating means for tilting the support 45 to feed wheel operative position includes a cam 57 driven by the shaft 22 through a one revolution clutch 58, a tappet lever 59 and a plunger or tappet means actuated by the cam comprising a pair of plunger members 60 and 61 working in a guide tube 62 and operatively connected together by a coiled spring 63, so that the plunger member 61, connected by a pin 64 to the opposite longer end of the lever support 45 from that of the bearing 41 of the shaft 36, may move relative to the plunger member 60 in case a coin should become jammed between the wheel and the discharge passage. Under these conditions the spring 63 is put under compression between the members 60 and 61, but the spring is only a yielding take up connection between these members and is not in itself an actuator. Details of the clutch 58 and lever 59 will be found in application Serial No. 181,713. The cam 57 is loose on the shaft 22 except when connected thereto by the clutch 58. Briefly, the clutch 58 has a toothed drive member 65 fixed to the shaft 22 and adapted to engage a spring pressed pawl 66 pivotally mounted on a disk portion 67 of the cam 57 and carrying a pin 68 which works in a slot (not shown) in the disk 67. When the pawl 66 under the action of its spring 69 is moved into operative relation with the toothed motor driven member 65, the cam 57 is rotated by said member 65 for one revolution and then said pawl is released by means controlled by the starting control of the predetermined count mechanism and acting on the pin 68 to throw the pawl 66 to an inoperative position. This means includes the holding and release lever 70 pivotally mounted at 71 on the frame of the machine and biased by a spring 72a toward the disk 67 and provided with a finger 72 engageable with the pin 68 to move said pawl to and hold it out of engagement with the drive member 65 so the cam 57 is free on the shaft 22. When, however, through the operation of a count starting control means hereinafter described, the lever 70 is swung toward the right as viewed in Fig. 3 and against the action of the spring 72a, it is released from holding engagement with the pin 68, so that the spring 69 then swings the pawl 66 inwardly to its clutched position with the drive member 65 and then as the shaft 22 continues to revolve, the cam 57 through the pawl 66 and member 65 is clutched to the shaft 22 and makes a single revolution during which the cam 57 through its pin projection 57a engages a roller 59a on the tappet lever 59 and swing the end 59b of said lever, engaging plunger part 60, upwardly and thus moves the plunger assembly including the part 61 upwardly and tilts the support 45 to bring the coin feeding wheel 15 into

coin feeding position, the parts then being in the position shown in Fig. 4. In this feeding position the parts are held by latching means forming a part of the present invention which includes a latch member 73 pivotally mounted at 14 on a part of the tube 62 and working through a slot in said tube and engageable within an annular slot 75 in the plunger part 60. The free end of the latch 73 is pivotally connected by a pin 76 to a plunger release link 77. Thus the cam 57 through lever 59 moves the plunger part 60 to a position where it is held by said latch and just before said cam completes its revolution, the pin 68 on the pawl 66 comes into contact with the finger 72 of the release lever 70 which then acts against said pin to push the pawl 66 out of driving contact with the drive member 65 and hold it out of driving position so that the cam 57 is released from the clutch 58.

The operation of the clutch control lever 10 and the latch 73 are controlled by mechanism associated with the predetermined count mechanism which is adapted to move the lever 10 to a position releasing said pin 68 so that the one revolution clutch 58 is effective to drive the cam 57 at the start of the count to bring the feed wheel 15 to coin feeding position and to move the latch 73 to a release position at the end of the count of a predetermined number of coins, so that the belt tensioner and spring 45a may swing the shaft 36 and the wheel 15 upwardly to an inoperative position. The predetermined count mechanism shown herein is similar in most respects to the Buchholz et al. Patent No. 2,378,828, but with certain hereinafter described modifications for acting on the latch 73 at the end of a predetermined count. So much of this mechanism has been shown as is deemed necessary for an understanding of the present invention, and this may be supplemented, if necessary, by referring to said patent.

As in the aforementioned patent, the number of coins to be counted is determined by the setting of a settable lever 78 of known form having an arm (not shown) adapted to engage a pin 79 on a counter operated ratchet wheel 80, said pin extending through an arcuate slot 81 in frame plate 82. As in the patent, the ratchet wheel 80 is turned in one direction by a spring 83 and in the opposite direction by a single tooth driver member 84 on the inner end of the counter drive shaft 13 that carries the star wheel 14. The wheel 80 is prevented from being turned backwardly by the spring 83 by a holding pawl 85 pivoted at 86. The tooth spacing of the wheel 80 is such that for five coins fed through the discharge passage on each revolution of the star wheel, said wheel 80 is advanced one tooth. For a continuous count, the lever 78 is moved so that the spring 83 may turn the wheel 80 to a position in which its toothed section is out of mesh with the cam or drive member 84. For predetermined counts the lever 78 acts on the pin 79 to set the wheel to a predetermined position, and as shown in Fig. 3, the wheel, which was set for the counting of ten coins, has been moved to a pre-set position as the seventh and eighth coins are counted as described in said patent. In the pre-set position shown, a positioning lever 87 pivoted in the shaft carrying the ratchet wheel 80 has been swung down against the action of a spring 88 by the engagement of a pin 89 on the wheel 80 with said lever 87 so as to bring a three armed lever 90 mounted on the lever 87 into a position in which it may

be operated upon by the drive member 84. The lever 87 has its positions determined by a spring pressed latch 91 cooperating with inclined shoulders 92 and 93 on the lever 87 whereby the downward swinging of the lever 87 as above described will be effective to disengage the latch 91 as shown in Fig. 3 as the seventh and eighth coins are counted. Thereafter, the drive member 84 is turned anti-clockwise as viewed in Fig. 3 as the ninth and tenth coins are fed past the star wheel and while the lever 87 is in its lowered position. While the tenth coin is passing the star wheel 14, the member 84 comes into engagement with a pin 95 on one of the arms of the three armed lever 90 which is pivotally mounted on the outer end of the positioning lever 87 corresponding to the lever 59 of said patent and swings said lever 90 clockwise, thereby causing a pin 96 on the second arm of said lever 90 working in a slot 85a in the holding pawl 85 to release said pawl and also causing the third arm of said lever to exert a pull to the left upon the plunger release link 77 which is pivotally connected to said third arm by a pin 77a and thus exert a pull on the free end of the latch 73 connected to the other end of the link 77 so as to swing it out of engagement with the notched slot 75 in the plunger part 60 so that the plunger means previously described is free to return to its initial position under the action of belt tensioner spring 56 and spring 45a and the wheel 15 is moved to its non-feeding position. As soon as the holding pawl 85 is released the spring 83 turns the wheel 80 to its initial position to start another count. The lever 90, link 77, and latch 73 are biased toward a latch engaging position and a holding pawl release position by a spring 97 anchored at one end to the tube 62 and connected at its other to the link 77, so that the driver 84 in swinging the lever 90 pulls against the tension of this spring to release said pawl 85 and latch 73. For starting the operation of the counting mechanism, the re-set or starting count control member 98, similar to the member 99 of the patent is pivoted on a pin 99 mounted on the frame plate 82 and has a hand lever extension 98a to which the link 31, previously referred to, is pivotally connected at 100, said member 98 being normally urged to an inoperative position by a spring 101. Member 98, as shown in Fig. 7, has a dog 102 pivotally mounted thereon at 103 which is adapted to engage a pin 104 on a pivoted latch 91, corresponding to the member 87 of said patent so as to swing said latch out of holding engagement with the lever 87, so that the spring 88 connected to said lever may swing it and the lever 90 back to their initial position in which the latch 91 engaging the shoulder 92 on the lever 87 holds the lever 90 out of engagement with the driver 84 until these parts are again swung down by the pin 89 on the wheel 80 to their lowered position slightly below that shown in Fig. 3, in which the drive member 84 is again effective to turn the ratchet wheel 80 and thereafter move the lever 90 as previously described. In addition to acting as a re-set member for the predetermined count mechanism, said member 98 also has a clutch release member 105 pivotally connected to it by a pin 106 and provided with a finger or projection 107 which is normally held in an operative position by a spring 108, which member 105 by having said finger 107 engage the finger 72 of the clutch release lever 70, as the control member 98 is operated to start the count, moves said finger 72 out of holding engagement

with the clutch pawl pin 68 so that the pawl 66 is moved by its spring 69 to an operative position with drive member 65 to connect the cam 57 to the shaft 22, so that through the operation of the connections of said cam with the support 45, said support will be tilted to bring the feed wheel 15 into operative association with the coins and move them past the star wheel. As soon as the lever extension 98a of the member 98 is released, the spring 101 swings the member 98 and the associated member 105 back to their initial position, so that the spring 72 may move the lever 70 back to a position permitting its release of the clutch as previously described. The feed wheel continues to operate until through the operation of the predetermined count, the lever 90, link 11, and latch 13 are operated to release the plunger 60 and permit the belt tensioner spring and spring 45a to restore the wheel 15 and its associated mechanism to an inoperative position simultaneously with the restoration of the predetermined count mechanism to its zero position.

In general the operation of the apparatus above described is the same as that of the copending applications with the exception of the arrangements for the wheel mounting and the release of the holding latch of the actuating means for the tiltable support, and the distinctions from these applications have been described in detail above. I desire it to be understood that this invention is not to be limited to any particular form or arrangement of parts except in so far as such limitations are included in the appended claims.

What I claim as my invention is:

1. In a coin counting machine of the type having a counting device and a continuously rotated

feed wheel for feeding coins past the counting device to actuate the same and in which an adjustable thickness gauge for accommodating the different denominations of coins is provided, the combination of a drive shaft for said feed wheel having an inner bearing and an outer bearing with a belt driven pulley adjacent said outer bearing, means directly pivotally mounting said outer bearing on said thickness gauge, and means for tilting said shaft about its pivotal mounting on said outer bearing comprising a tiltable lever pivotally mounted on said thickness gauge and carrying said inner bearing, and actuating means for said lever to tilt said shaft about said outer bearing to a feed wheel operative position.

2. In a coin counting machine of the type having a counting device and a continuously rotated feed wheel for feeding coins past the counting device to actuate the same and in which an adjustable thickness gauge for accommodating the different denominations of coins is provided, the combination of a drive shaft for said feed wheel having an inner bearing and an outer bearing with a belt driven pulley adjacent said outer bearing, means directly pivotally mounting said outer bearing on said thickness gauge, and means for tilting said shaft about its pivotal mounting on said outer bearing comprising a tiltable lever pivotally mounted on said thickness gauge having a short arm carrying said inner bearing and a long arm, and actuating means for said lever connected with the outer end of said long arm to tilt said shaft about said outer bearing to a feed wheel operative position.

ARNOLD R. BUCHHOLZ.
